US00D926019S

(12) **United States Design Patent** (10) **Patent No.:** **US D926,019 S**
(45) **Date of Patent:** **** Jul. 27, 2021**

(54) **SUPPORTING DEVICE OF LOCK AND ATTACHMENT MECHANISM**

(71) Applicant: **NAGAKI SEIKI CO., LTD.**, Daito (JP)

(72) Inventor: **Tomohiro Orikawa**, Aomori (JP)

(73) Assignee: **NAGAKI SEIKI CO., LTD.**, Daito (JP)

(**) Term: **15 Years**

(21) Appl. No.: **29/621,062**

(22) Filed: **Oct. 4, 2017**

(30) **Foreign Application Priority Data**

Apr. 7, 2017 (JP) 2017-007480

CLAIM

The ornamental design for a supporting device of lock and attachment mechanism, as shown and described.

DESCRIPTION

FIG. 1 is a front view of the supporting device of lock and attachment mechanism;

FIG. 2 is a rear view thereof;

FIG. 3 is a top view thereof;

FIG. 4 is a bottom view thereof;

FIG. 5 is a right side view thereof;

FIG. 6 is a left side view thereof; and,

FIG. 7 is a perspective view thereof.

The broken lines illustrate unclaimed subject matter and form no part of the claimed invention.

1 Claim, 2 Drawing Sheets
